CLASP FOR HAIR ORNAMENTS

Stephen F. Kayn and Daniel D. Whyte, New York, N. Y., assignors to Injection Moulding Corp., New York, N. Y., a corporation of New York

Application October 19, 1937, Serial No. 169,757

5 Claims. (Cl. 132—47)

This invention relates to improvements in clasps, for hair ornaments or the like.

Up to the present time, decorative articles such as ribbons, flowers or the like, have been applied to the hair by means of attached pins, hooks, or the like, interwound with the hair, with the result that the same have become easily separated, more particularly upon disturbance.

Broadly, it is an object of this invention to provide for an ornamental clasp having engagement members on opposite faces, one for the hair upon which the clasp is mounted and the other for ribbons, flowers or like decorative media.

Specifically, it is an object of this invention to provide a clasp for attaching decorative media such as flowers, ribbons, and the like, to the hair, involving a decorative unit attachable on one face to the hair and having means on the other face for insertion in or engagement with decorative media for the hair.

These and other advantages, capabilities and features of the invention will appear from the subjoined detailed description of one specific embodiment thereof illustrated in the accompanying drawing, in which—

Figure 1 is a plan view of a clasp for ornaments or the like.

Figure 2 is a front elevation of the clasp as applied to the head.

Figure 3 is a bottom view of the clasp.

Figure 4 is an end elevation in section taken along lines 3—3 of Figure 2.

Figure 5 is an end elevation in section taken along lines 4—4 of Figure 2.

Figure 6 is a front elevation of a modified form of clasp as applied to the head.

Referring to the reference characters in the drawing, numeral 10 represents a clasp body portion formed of plastic material having disposed on its upper or outer face 11 fastener assembly 13, and on its lower or inner face 12 fastener assembly 14, both being pivotally mounted, the first functioning by a horizontal displacement, and the latter functioning by a vertical displacement.

As shown in Figures 1 and 2, the fastener assembly 13 on the upper face 11 of the clasp comprises a resilient swivel element 15 in the nature of a bowed band, one end or arm 16 of which is pivotally mounted on shank 17 and maintained for horizontal displacement by head 18 of an eyelet embedded in body 10, the intermediate section 19 of the swivel element 15 being bowed upwardly, and the free end or arm 20 thereof having a portion in the same plane as arm 16

and adapted to rest against face 11, the extreme end of free arm 20 of the swivel element having a downwardly bowed projection 21 resting in groove 22 formed in face 11 of the body member, thereby to provide for a positive latching for the fastener assembly 13 to the body.

On the other face 12 of the body there is mounted a second swivel fastening assembly actuatable in the vertical plane, comprising a U-shaped spring wire tongue 23 looped as indicated, having side walls 24 and 25 leading from the closed end 26 thereof, said tongue being bowed inwardly and clamped at 27 adjacent the inwardly bent free ends 28 and 29, resting in horizontal aperture 30 of lug 31, which is integral with and projects from one end of face 12, thereby providing a pivotally mounted vertically displaceable locking element. At the other end of face 12 there is disposed a vertically upstanding pillar 20 having parallel horizontal grooves 32 oppositely disposed on its shank 33, the walls 24 and 25 of the tongue, adjacent the closed end 26 thereof, being normally spaced a distance less than the diameter of the pillar so that when the resilient tongue is depressed in the direction shown in Figure 2, from that of the dotted lines to the full lines, such walls are expanded through contact with the shank 33 of the pillar, and then upon attaining the grooves 32 of the shank, the pressure being removed, the walls return to their initial condition and rest in the grooves to firmly clamp the tongue to the pillar; the tongue being of such resiliency that a vertical movement with respect to the pillar will latch or unlatch the fastening element 14.

As shown in Figure 2, a ribbon or like decoration 34 may be mounted on the body 10 by passing the free end 20 of the fastening member 13 through a loop 35 of the ribbon, such loop being positioned at the bowed portion 19 of the fastening element.

The body or clasp carrying the ribbon or the like may be applied to the head by enclosing through the gripping action of fastening element 14 a series of strands of hair disposed between 45 the tongue 23 and face 12 of the clasp, and thereafter latching the tongue to the pillar.

As shown in Figure 6, the clasp may be of a construction to incorporate on both sides fastening assemblies of either of the types shown in Figures 1 to 3, this modification serving to disclose fastening assemblies 14. In this modification the decorative article such as the flower or the like, 36, having a stem, may be maintained by pressure between one of the faces of the clasp 55

and the swivel fastening element, as for example, the tongue; the fastening assembly on the other side of the clasp serving to associate the clasp for mounting on the hair or any other medium.

5 It is obvious that various changes and modifications may be made to the details of construction without departing from the general spirit of the invention as set forth in the appended claims.

We claim:

- 10 1. An ornamental clasp comprising a body portion, and a plurality of fastening devices on opposite faces thereof, each of said fastening devices comprising a swivel member and a latch therefor, the swivel member of one of said fastening devices being actuatable for horizontal displacement about a vertical axis and the swivel member of the other of said devices being actuatable for vertical displacement about a horizontal axis.
- 15 2. An ornamental clasp comprising a body portion and a fastening device disposed on one of the faces of said clasp, said fastening device comprising a resilient swivel member pivoted at one end to the body of the clasp for horizontal displacement about a vertical axis, and having at one end thereof, a depending projection, and a groove formed in said body into which said depending projection may be disposed for latching the swivel member to the body.
- 20 3. An ornamental clasp comprising a body portion, and fastening devices on opposite faces of said body portion, the respective fastening devices each consisting of a swivel member at one

end of said body member, one of said swivel members being displaceable in the horizontal plane about a vertical axis and the other of said swivel members being displaceable in the vertical plane about a horizontal axis, the intermediate portions of said swivel members being spaced from the body to permit insertion of a medium between the swivel member and the body for clamping the same, and means on the respective faces of said body member cooperating with the free ends of 10 said swivel members for latching the same.

4. An ornamental clasp comprising a body portion and a fastening device disposed on one of the faces of said body portion, said fastening device comprising a resilient swivel member pivoted 15 at one end to the body portion for horizontal displacement about a vertical axis, and means on said body portion cooperating with the free end of said swivel member for latching the same to the body portion.

5. An ornamental clasp comprising a body portion and a fastening device disposed on one of the faces of said body portion, said fastening device comprising a resilient swivel member pivoted at one end to the body portion for horizontal 25 displacement about a vertical axis, an offset tongue formed at the free end of said swivel member and a groove formed in said body portion into which said offset tongue may be displaced for latching the swivel member to the body portion. 30
